ATTORNEY

UNITED STATES PATENT OFFICE.

MERWIN T. MIFFLIN, OF DUQUOIN, ILLINOIS.

DESIGN FOR A DOLL, STATUETTE, OR SIMILAR ARTICLE.

61,316.

Specification for Design.

Patented Aug. 1, 1922.

Application filed February 8, 1922. Serial No. 592. Term of patent 14 years.

To all whom it may concern:

Be it known that I, MERWIN T. MIFFLIN, a citizen of the United States, residing in the city of Duquoin and State of Illinois, have invented a new, original, and ornamental Design for Dolls, Statuettes, or Similar Articles, of which the following is a specification, reference being had to the accompanying drawing, forming part thereof.

In the drawing the figure is a front perspective view of a doll or statuette illustrating my new design.

I claim:

The ornamental design for a doll, statuette, or similar article substantially as shown.

MERWIN T. MIFFLIN.
